UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

SUPPORT FOR CURTAIN-ROD ORNAMENTS

Application filed June 24, 1929. Serial No. 373,093.

This invention relates to an improved supporting device for the end ornament of curtain rods. One popular style of curtain rod now in vogue consists of a plain rod, to the 5 central and end portions of which are attached, usually by C-shaped spring clips embracing the front wall and upper and lower edges of the rod, stamped sheet metal ornaments in various configurations and colors. 10 The end ornaments are usually mounted on the rod just inwardly of the elbow end portions of the latter, and extend outwardly so that the elbow end portion of the rod is substantially concealed by the ornament. 15 The shank or stem portion of the ornament is flexible and rather easily bent, so that not infrequently the ornament, in the shipment or subsequent handling of the rod, becomes more or less displaced from its true position 20 substantially in line with the main portion of the rod, where a plain C-shaped clip attached to the shank of the ornament and embracing the rod, is employed as the attaching means. 25 The object of the present invention is to provide a simple and efficient device auxiliary to the attachment clip for supporting the ornament in its true position and preventing the backward bend or misalignment of the 30 ornament relatively to the rod.

In the accompanying drawing I have illustrated two simple mechanical embodiments of the invention, both embodying the principle of a back strut or brace on the rear side of 35 the ornament which abuts against the curved portion of the elbow end of the rod and, in cooperation with the attaching clip, maintains the ornament in substantial alignment with the main portion of the rod to which it 40 is attached, and referring thereto—

Fig. 1 is a front elevation of the end portion of the curtain rod showing the ornament applied thereto.

Fig. 2 is a plan section on the line 2—2 of 45 Fig. 1.

Fig. 3 is a perspective detail of the combined clip and brace shown in Figs. 1 and 2.

Fig. 4 is a plan section illustrating a modification wherein the strut or brace is formed 50 integral with the ornament.

Fig. 5 is a perspective of the attaching clip employed in the structure illustrated in Fig. 4.

Referring first to Figs. 1, 2 and 3, 10 designates a fragment of the intermediate portion of an ordinary flat sheet metal telescoping curtain rod, continuous with which is the usual elbow end portion 11 that is mounted in or on a bracket (not shown) attached to the 55 window frame.

12 designates as an entirety a stamped sheet metal end ornament that is mounted on the rod portion 10 and serves to conceal from front view the elbow end 11 and its supporting bracket. The ornament 12 is die pressed from thin sheet metal and includes a flat 60 stem or shank portion 12'. To the inner side of the shank 12' is attached, as by a rivet 13, an integral or one-piece clip and brace cut and bent from a sheet metal blank to the 65 form illustrated in Fig. 3, and comprising a C-shaped clip 14 which straddles the front face and upper and lower edges of the rod section 10, a laterally projecting arm 15 apertured as at 16 to receive the rivet 13, and a rearwardly inclined extension 15' of the 70 arm 15 which bears on the rounded outer surface of the elbow end 11 of the rod, as clearly shown in Fig. 2. The arm extension 15' thus serves, in cooperation with the clip 75 14, as a strut or brace to resist rearward deflection of the ornament 12, and maintains the latter in its true position substantially in alignment with the main section 10 of the 80 rod.

These ornaments are sometimes made of cast metal, instead of being die pressed from sheet metal. In Fig. 4 is illustrated in longitudinal section such a cast metal ornament 85 at 17, to the inner end or shank 17' of which is attached as by a rivet 18 a plain C-shaped clip 19, shown in detail in Fig. 5. In this case I cast on the rear side of the ornament a brace or strut 20, the free end of which bears 90 on the outer rounded surface of the elbow end 11 and performs, in cooperation with the clip 19, the same function as the brace or strut 15' shown in Fig. 2.

I claim:

1. In combination with a curtain rod orna- 923

ment, means for attaching said ornament to a curtain rod, and a brace laterally offset from said attaching means between the rear surface of the ornament and the rod adapted to bear on the latter.

5. In combination with a curtain rod ornament, an attaching clip secured to said ornament and adapted to embrace a curtain rod, and a brace laterally offset from said attaching clip between the rear surface of the ornament and the rod adapted to bear on the latter.

10. In combination with a curtain rod ornament, an attaching clip secured to said ornament and adapted to embrace a curtain rod, and a laterally extending brace integral with said clip adapted to bear at its free end against the face of the rod.

15. In combination with a curtain rod ornament, an attaching clip secured to the inner end portion of said ornament and adapted to embrace a curtain rod adjacent to an elbow end portion of the latter, and a brace fast with the rear side of said ornament having a free end portion adapted to bear against 20 the elbow end portion of the rod.

25. In combination with a curtain rod ornament, an attaching clip secured to the inner end portion of said ornament and adapted to embrace a curtain rod adjacent to an elbow 30 end portion of the latter, and a laterally extending arm on said clip formed with a rearwardly bent portion adapted to bear at its free end on said elbow end portion of the rod.

JAMES H. BOYE.
